CLAIM

The ornamental design for a display screen or portion thereof with graphical user interface, as shown and described.

DESCRIPTION

FIG. 1 is a front view of a graphical user interface for a display screen or portion thereof showing our new design. FIG. 2 is a front view of another embodiment of our new design.

FIG. 3 is a front view of another embodiment of our new design; and,

FIG. 4 is a front view of another embodiment of our new design.

The dot-dash broken lines showing a display screen or portion thereof illustrate portions of the article and form no part of the claimed design.

1 Claim, 3 Drawing Sheets
